BY *Donald Webster* ATTORNEY

UNITED STATES PATENT OFFICE.

CHARLES H. GUNN AND JOHN C. NEWCOMB, OF OAKLAND, CALIFORNIA.

BRACE FOR WASHTRAYS.

Application filed August 1, 1923. Serial No. 655,007.

To all whom it may concern:

Be it known that we, CHARLES H. GUNN and JOHN C. NEWCOMB, citizens of the United States, residing at Oakland, county 5 of Alameda, State of California, have invented certain new and useful Improvements in Braces for Washtrays; and we do declare the following to be a full, clear, and exact description of the same, reference 10 being had to the accompanying drawings, and to the characters of reference marked thereon, which form a part of this application.

This invention relates to improvements in 15 brackets and particularly relates to a bracket for supporting wash trays.

Wash trays are most commonly made up of cement or similar material molded into one member with a center partition dividing 20 the member into two trays. These trays are usually simply mounted on two supporting legs and in the present type of plumbing have no brackets or supporting means for securing them to the wall so as 25 to prevent undue movement thereof.

It has been found in practice that as thus unsupported the weight of the water and the various operations carried on in and about the trays during the washing operation, 30 is such as to tend to vibrate or move the trays to such a degree that they often fall over or collapse. This condition is not only very disagreeable, but also quite dangerous, in view of the extreme weight 35 of the trays, which averages about four or five hundred pounds.

It is therefore the object of our invention to produce a bracket which is adapted to co-operate with the present type of plumbing 40 and to engage the center partition wall of the trays in such a manner as to hold the trays rigid and immovable so as to obviate the conditions as above enumerated.

A further object of the invention is to 45 produce a simple and inexpensive device and yet one which will be exceedingly effective for the purposes for which it is designed.

These objects we accomplish by means of 50 such structure and relative arrangement of parts as will fully appear by a perusal of the following specification and claims.

In the drawings similar characters of reference indicate corresponding parts in the 55 several views:

Fig. 1 shows a dotted outline of the wash

trays and the modern type of plumbing in connection therewith showing, in full lines, our improved bracket installed thereon.

Fig. 2 is a perspective view of our improved bracket.

Referring now more particularly to the characters of reference on the drawings, the numeral 1 designates the trays, while 60 2 is the central partition above referred to. 65 In the present type of plumbing the water is lead to a point above the trays through two extended nipples 3 to each of which is connected a valve 4, one for the hot water and one for the cold. From the valves 4 70 pipes 5 lead to a central outlet 6 of the desired type.

With the old style of plumbing where a pair of outlet pipes was used for each tray, 75 these pipes would project directly through the back wall of each tray and would form a substantial brace for the same. With the type of plumbing above identified, however, it will be apparent that there is no possible way of supporting the trays as in the past, 80 and as already stated, to our knowledge, there has been no other way provided to take care of this condition, and hence our improved bracket is provided for that purpose.

Our bracket consists essentially of a bifurcated yoke 7 adapted to fit over the center partition 2 and be firmly engaged therewith by means of a set screw 8. Two 90 upwardly projecting arms 9 are formed on the yoke 7, each arm being provided with a longitudinal slot 10 and having its under face provided with serrations 11. Numeral 12 designates adjustable extensions for the arms 9, such extensions having serrations 95 13 on their upper faces engageable with the serrations 11. Set screws 14 extend through the slots 10 and engage the extensions 12 to adjustably connect such extensions with the arms 9.

On the outer ends of the extensions 12 are semi-circular yokes 15 adapted to engage the nipples 3.

In practice, if the trays 1 are set in position and the plumbing installed the yokes 15 are engaged with the nipples 3. Then through the medium of the adjustable arms 9-12 the yoke 7 is fitted in position over the partition 2. The set screws 8 and 14 are then tightened. It will be apparent that the 105 bracket, as thus installed, will suitably brace the trays against both lateral and transverse 110

movement, hold then rigidly in place and obviate the difficulties herein first enumerated.

From the foregoing description it will be readily seen that we have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described our invention what we claim as new and useful and desire to secure by Letters Patent is:

1. A bracket comprising a bifurcated yoke, means for fixing the yoke in position, and opposed arms extending outwardly and upwardly from the yoke and provided with engaging means at their outer ends.

2. A bracket comprising a bifurcated yoke, means for fixing the yoke in position, and adjustable opposed arms extending outwardly

and upwardly from the yoke and provided with engaging means at their outer ends.

3. A bracket comprising a bifurcated yoke, a set screw threaded through one side of the yoke, opposed arms extending upwardly from the yoke, and engaging means on the outer ends of the arms.

4. A bracket comprising a bifurcated yoke, opposed arms extending outwardly from the yoke and provided with longitudinal slots, extensions for such arms formed as a continuation thereof and having set screws movable through the slots, and engaging means on the outer ends of the extensions.

5. A brace for wash trays having a central partition and pipes above said partition on both sides thereof and parallel thereto, comprising a yoke to engage the partition, yokes to engage the pipes and rigid arms connecting the first and last named yokes.

In testimony whereof we affix our signatures.

CHARLES H. GUNN.
JOHN C. NEWCOMB.
